UNITED STATES PATENT OFFICE.

DAVID JOHN SCOTT, OF PLAINFIELD, NEW JERSEY, ASSIGNOR TO ISABELLA SCOTT AND DAVID J. SCOTT, EXECUTORS OF WALTER SCOTT, DECEASED.

WEB-PERFECTING MACHINE.

1,284,475.

Specification of Letters Patent. Patented Nov. 12, 1918.

Original application filed April 2, 1915, Serial No. 18,639. Divided and this application filed September 29, 1916. Serial No. 122,837.

To all whom it may concern:

Be it known that I, DAVID J. SCOTT, a citizen of the United States, and a resident of Plainfield, in the county of Union and State 5 of New Jersey, have invented certain new and useful Improvements in Web-Perfecting Machines, of which the following is a specification.

The present invention relates generally to 10 offset perfecting machines and has more particularly reference to the general arrangement of the printing units composing such machine; and is a division of the application filed by me Apr. 2, 1915, Ser. No. 18,639.

15 The main object of the invention is to provide a machine in which both sides of the web are printed by the offset process, and without the omission of elements necessary to produce high class results; and in which 20 the arrangement of cylinders is such that all the working parts will be readily accessible.

Another object of this invention is to provide means for conveniently controlling the 25 various instrumentalities that comprise the press.

Accordingly, the invention consists of the 30 features of construction, combination of parts and arrangement of elements herein-after described, a preferred form of which is disclosed in the accompanying drawings. However, changes may be made in the particular form shown herein without departing 35 from the legitimate and intended scope of the invention as expressed in the appended claims.

In the said drawings:

Figure 1 is a plan view, largely in dia- 40 grammatic form, of a machine embodying the invention.

Fig. 2 is a view in elevation of the parts 45 shown in Fig. 1, looking in the direction of arrow 2 of Fig. 1.

Fig. 3 is a detail view, in elevation, of the 50 first printing couple.

The machine comprises two units, each 55 unit consisting of a form-carrying cylinder, a transfer cylinder and an impression cylinder. The form-carrying cylinder is marked A in the first unit and B in the second unit, while the transfer cylinder is marked C in the first unit and D in the second unit, and the impression cylinder is marked E in the first unit and F in the second unit. The

form-carrying and transfer cylinders of each 55 unit are arranged to form an exposed operating side with the impression cylinder non-adjacent to the operating side, and the two units are grouped with their cylinders end to end and with their operating sides outer- 60 most. I indicates a source of supply, here shown as a roll of paper, and L indicates a delivery mechanism conveniently represented as a former folder, said source and said delivery being arranged end to end and 65 located alongside the printing units and non-adjacent to the operating sides thereof but adjacent the impression cylinders. The source I is opposite the first unit and the delivery is opposite the second unit; and, in- 70 termediate the units, the source and the delivery are devices for guiding the paper which, in the present instance, take the following form: The web X is led from source I over guide rollers X' straight across to 75 the impression cylinder E of the first printing unit. From thence the paper passes around cylinder E and back to turner bar X¹⁴ where it is given a quarter turn, and passes over to turner bar X¹⁵ where it re- 80 ceives another quarter turn that directs it to impression member F of the second printing unit. The paper then passes around said impression cylinder F to guide rollers X¹⁶ and thence to the delivery L. The paper, 85 in passing from the impression member of the first printing unit to the impression member of the second unit, has been reversed so that the printed side will come in contact with the surface of impression cyl- 90 nder F. Also, the paper in passing to and from impression cylinder F is doubled-back upon itself; and, intermediate the web runs of this double-back portion, there is inter- 95 posed an anti-smutting device 37 engaging with the surface of impression cylinder F. The anti-smutting device 37 is for the purpose of preventing the printed side of the paper from soiling the surface of impres- 100 sion cylinder F.

Associated with each form-carrying cyl- 105 nder is an inking mechanism O, and, should the character of the work require it, dampening mechanisms N.

54 indicates sliding boxes in which trans- 105 fer cylinders C and D are mounted, and are controlled from operating handles 34 whereby said transfer cylinders may be moved

outwardly of the operating side of the units to admit of manipulation by the pressman. Likewise impression cylinders E and F are mounted in sliding boxes 54 controlled 5 from handles 35 whereby said impression cylinders may be thrown off the transfer cylinders. The anti-smutting device 37 is mounted on the sliding box 54 of impression cylinder F so that the two are 10 moved bodily in unison. This feature is claimed in a companion application, Serial No. 122,833, filed Sept. 29, 1916, as is also the broad feature of interposing the anti-smutting device between the double-back 15 portions of the web. The dampening mechanisms N may be thrown off the form carrying cylinders A and B by means of handles 38.

What is claimed, is:

- 20 1. A rotary offset perfecting machine comprising: a plurality of units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders to afford an exposed operating side for the unit, said units being grouped with their operating sides outermost and with their cylinders end to end, a source of impression receiving material, delivery mechanism located non-adjacent to the operating sides of the units, and means between said units, said source and said delivery mechanism for feeding the impression receiving material to the impression cylinder of one unit, transferring it to the impression cylinder of the other unit and then transferring it to the delivery mechanism.

- 25 2. A rotary offset perfecting machine comprising: a plurality of units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders to afford an exposed operating side for the unit, said units being grouped 30 with their operating sides outermost and with their cylinders end to end, a source of impression receiving material, delivery mechanism located non-adjacent to the operating sides of the units, means between said units, said source and said delivery mechanism for feeding the impression receiving material to the impression cylinder of one unit, transferring it to the impression cylinder of the other unit and then transferring it to the delivery mechanism,

35 and means for moving the transfer cylinders outwardly with respect to the operating sides of the units.

3. A rotary offset perfecting machine comprising: a plurality of units printing 70 from positive forms on opposite sides of impression receiving material, each unit consisting of a form-carrying, a transfer and an impression cylinder all of substantially the same diameter, the form carrying and 75 transfer cylinders being arranged in an upright column and the impression cylinder being arranged out of line with the other cylinders to afford an exposed operating side for the unit, said units being grouped with 80 their operating sides outermost and with their cylinders end to end, a source of impression receiving material, delivery mechanism located non-adjacent to the operating sides of the units, means between said units, 85 said source and said delivery mechanism for feeding the impression receiving material to the impression cylinder of one unit, transferring it to the impression cylinder of the other unit and then transferring it to the delivery mechanism, the paper in passing to and from the impression cylinder of the second unit being doubled back upon itself, and 90 an anti-smutting device engaging with the impression cylinder of the second unit and 95 located between the runs of the double-back web.

4. An offset perfecting machine comprising: a plurality of units, each unit including a form-carrying, a transfer and an impression member, the form-carrying and transfer members being arranged to form an exposed operating side for each unit with the impression member non-adjacent to the operating side, said units being grouped 100 with their operating sides outermost and with their members end to end, a source of impression receiving material and delivery mechanism located non-adjacent to the operating sides of the units and adjacent to the 110 impression members, means for feeding paper from the source of supply to the impression member of the first unit, then transferring it to the impression member of the second unit with its printed side against 115 said impression member, and then transferring it to the delivery mechanism, the paper in passing to and from the impression member of the second unit being doubled back upon itself, an anti-smutting device engaging 120 the surface of the impression member of the second unit and intermediate the runs of the double-back portion of the web, and means for moving the impression member of the second unit and the anti-smutting device bodily away from the transfer member.

5. An offset perfecting machine comprising: a plurality of units, each unit including a form-carrying, a transfer and an impression cylinder, the form-carrying and 125 transfer cylinder being arranged in an upright column and the impression cylinder being arranged out of line with the other cylinders to afford an exposed operating side for the unit, said units being grouped 130 with their operating sides outermost and with their cylinders end to end, a source of impression receiving material, delivery mechanism located non-adjacent to the operating sides of the units, means between said units, said source and said delivery mechanism for feeding the impression receiving material to the impression cylinder of one unit, transferring it to the impression cylinder of the other unit and then transferring it to the delivery mechanism,

transfer cylinders being arranged to form an exposed operating side for each unit with the impression cylinder non-adjacent to the operating side, said units being grouped 5 with their operating sides outermost and with their cylinders end to end, a source of impression receiving material and delivery mechanism located non-adjacent to the operating sides of the units and adjacent to the 10 impression cylinders, means for feeding paper from the source of supply to the impression cylinder of the first unit, then transferring it to the impression cylinder of the second unit with its printed side against 15 said impression cylinder, and then transferring it to the delivery mechanism, the paper

in passing to and from the impression cylinder of the second unit being doubled back upon itself, an anti-smutting device engaging the surface of the impression cylinder 20 of the second unit and intermediate the runs of the doubled-back portion of the web, and means for moving the impression cylinder of the second unit and the anti-smutting device bodily away from the transfer cylinder. 25

Signed at Plainfield, in the county of Union and State of New Jersey, this 27th day of September, A. D. 1916.

DAVID JOHN SCOTT.
